DINNER PLATE OR THE LIKE

Leighton D. Hubbard, San Francisco, Calif., assignor to Nicosia-Hubbard Corporation, San Francisco, Calif., a corporation of California

Application July 21, 1954, Serial No. 31,522

Term of patent 3½ years

(Cl. D44—15)

Fig. 1 is a top plan view of a dinner plate showing my new design;

Fig. 2 is a side elevational view thereof;

Fig. 3 is a sectional view thereof taken along the line 3—3 in Fig. 1;

Fig. 4 is a bottom plan view of the plate as shown in Fig. 1;

Fig. 5 is a front elevational view thereof;

Fig. 6 is a rear elevational view thereof;

Fig. 7 is a sectional view thereof taken along the line 7—7 in Fig. 1; and

Fig. 8 is a sectional view thereof taken along the line 8—8 in Fig. 1.

I claim:

The ornamental design for a dinner plate or the like, substantially shown.
